US00D324857S

United States Patent [19]

Kuo

[11] Patent Number: Des. 324,857

[45] Date of Patent: ** Mar. 24, 1992

[54] IMAGE SCANNER

[75] Inventor: Sean Kuo, Hsinchu, Taiwan

[73] Assignee: Microtek International, Inc., Hsinchi, Taiwan

[**] Term: 14 Years

[21] Appl. No.: 435,575

[22] Filed: Nov. 13, 1989

[30] Foreign Application Priority Data

Jul. 21, 1989 [JP] Japan 1-26762

[52] U.S. Cl. D14/107
